DESIGN FOR A WAGON

Gordon W. Florian, Long Hill, Conn.

Application July 11, 1946, Serial No. 131,505

Term of patent 7 years

(Cl. D34—15)

To all whom it may concern:

Be it known that I, Gordon W. Florian, a citizen of the United States, residing at Long Hill, in Fairfield County and the State of Connecticut, have invented a new, original, and ornamental Design for a Wagon, of which the following is a specification, reference being had to the accompanying drawing, forming part thereof.

Fig. 1 is a perspective view of a wagon showing my new design;

Fig. 2 is a plan view thereof on a larger scale;

Fig. 3 is a side elevational view thereof on the scale of Fig. 2; and

Fig. 4 is a front elevational view thereof.

I claim:

The ornamental design for a wagon, substantially as shown.

GORDON W. FLORIAN.
